US0D1001019S

(12) **United States Design Patent** (10) Patent No.: **US D1,001,019 S**
(45) Date of Patent: ** Oct. 10, 2023

(54) **BICYCLE**

(71) Applicant: **Woom GmbH**, Klosterneuburg (AT)

(72) Inventor: **Matthias Leite-Gürtner**,
Klosterneuburg (AT)

(73) Assignee: **WOOM GMBH**, Klosterneuburg (AT)

(**) Term: **15 Years**

(21) Appl. No.: **35/514,223**

(22) Filed: **Feb. 17, 2022**

(80) **Hague Agreement Data**

Int. Filing Date: **Feb. 17, 2022**

Int. Reg. No.: **DM/220449**

Int. Reg. Date: **Feb. 17, 2022**

Int. Reg. Pub. Date: **May 6, 2022**
